PORTABLE SCOURING AND POLISHING MACHINE OF THE ROTARY DISK TYPE

Louis Zaiger, Swampscott, Mass.

Application November 22, 1949, Serial No. 128,701

3 Claims. (Cl. 15—98)

This invention pertains to a portable scouring and 15 polishing machine of the rotary type wherein an electric motor, housed within a casing, drives a shaft to whose end a scouring or polishing disk or the like may be secured and wherein the casing has handle means for use in manipulating the machine in moving the polishing 20 or scouring element over the work. Portable machines of this type are commonly used for finishing, refinishing or polishing articles of furniture, for polishing automobile bodies or for waxing and polishing floors. When designed primarily for operation upon elevated objects such as objects of furniture or the like, the machine is usually provided with a short, rigid handle of convenient shape to be grasped in the hand of the user, the handle being fixed to the casing and commonly projecting at approximately right angles to the shaft or spindle which carries the polishing or scouring element. While it is possible to use such an arrangement for sanding or waxing a floor, such use makes it necessary for the user to assume a kneeling position which is not convenient, especially when treating large areas. For many persons such 35 a mode of operation would be wholly impractical. On the other hand, machines designed primarily for sanding or waxing floors usually have long, upstanding, and often heavy, handles by means of which the user may propel the apparatus along the floor while in a standing position. Such devices, by reason of the length and weight of the handle, are not convenient nor practical for use in furniture polishing or similar operations.

The principal object of the present invention is to provide improved apparatus of the above general type which is capable of and convenient for use in such operations as polishing furniture, automobile bodies and the like, and also for floor sanding or polishing. A further object is to provide a portable scouring and polishing machine having handle means so designed that it may be grasped in one hand for supporting and manipulating the apparatus when working on elevated objects such as furniture, automobile bodies and the like, but which is likewise so devised that it may be used for propelling the apparatus along the floor while the user is in standing position. A further object is to provide a portable machine of the above type having a handle which may be fixed in a plurality of positions and which may be made shorter or longer at will. Other and further objects and advantages of the invention will be pointed out in the following more detailed description and by reference to the accompanying drawings wherein

Fig. 1 is a side elevation illustrating the apparatus of the present invention with its handle arranged in one position of use;

Fig. 2 is a side elevation showing the lower part of the casing of the apparatus, with the hand grip in horizontal position and with the spindle partly in section, the disk being omitted;

Fig. 3 is a side elevation of the disk which carries the polishing element;

Fig. 4 is a fragmentary, plan view of the parts shown in Fig. 1;

Fig. 5 is a fragmentary, vertical section through the outer end of the hand grip device of Figs. 1, 2 and 3, showing a portion of an extension rod or handle attached thereto; and

Fig. 6 is a side elevation showing the apparatus provided with a sectional extension handle useful in propelling the apparatus along the floor in sanding or polishing the floor.

2

Referring to the drawings, the numeral 1 designates the apparatus as a whole. As here illustrated the machine comprises a casing having a base or bottom portion 2 which may be an integral metallic casting, for example of aluminum, or which may be molded from other material, for instance a suitable synthetic resin, this base, as here illustrated, being cup-like in shape and designed to constitute a support for the electric motor (not shown) and to provide a bearing for the normally vertical shaft or spindle which carries the polishing or scouring element. As illustrated, the casing also comprises an upper part 3, here shown as of inverted, cup-like shape, desirably of thin sheet metal or the like, and having openings for ventilating the motor. Preferably a gasket 4 of resilient or sound deadening material is interposed between the lower edge of the part 3 and the base 2. The several parts of the casing are united in any appropriate manner, for example by bolts or screws. The motor is supplied with current through a flexible conductor 5. The motor may be arranged with its shaft coaxial with the axis of the casing, the shaft then extending down through the bearing in the lower part of the base 2 and forming the immediate support for the disk which carries the polishing and scouring elements. Under such circumstances the spindle or shaft is driven at the motor speed. However, it is preferred to interpose speed reduction gearing (not shown) between the motor and the spindle or shaft 6 to which the polishing disk is secured in order that the speed of rotation of the polishing disk may be less than that of the motor, thus avoiding the possibility of overheating the work during the scouring or polishing operation. The lower end of the spindle or shaft 6 (Fig. 2) is provided, as is usual in such machines, with an axial, screw threaded bore designed to receive a screw threaded axial boss 7 (Fig. 3) at the upper end of the stem 8 of the disk 9 on which the scouring or polishing element is mounted. As illustrated in Fig. 1 a thick polishing pad 10 of soft material such as felt or wool is mounted in the disk 9.

As herein illustrated, the base 2 is provided with an integral outstanding lateral boss 11. This boss has a vertical outer surface 12 and a second vertical surface or shoulder 13. A handle element 14, here shown as a hollow hand grip properly designed and shaped to be grasped in the hand of the user, is connected to the boss 11 for use in manipulating the apparatus when operating upon elevated objects (as contrasted with use on the floor). As illustrated, this hand grip member 14 is made from stiff sheet metal and at its inner end is provided with spaced, parallel ears 15 and 16 (Fig. 4) which are designed to receive the boss 11 between them, these ears 15 and 16 being provided with aligned openings for the reception of a bolt 17 which passes through these openings and through an opening in the boss 11 and which is provided with a wing nut 18 by means of which the parts may be tightened so as to hold the hand grip 14 in a desired position of adjustment. The surfaces 12 and 13 of the boss form limiting elements for the hand grip and together with the bolt 17 constitute a knuckle joint permitting the hand grip to be swung from the horizontal position of Fig. 2 (wherein a shoulder 19 (Fig. 1) of the hand grip contacts the surface 12 of the boss 11) to a position wherein another shoulder 20 (Fig. 1) of the hand grip contacts the vertical surface 13 of the boss 11. As illustrated, this permits an arc of movement of approximately 45°, although by varying the positions of the shoulders 19 and 20 such arc of movement might be varied, if desired.

The flexible conductor 5 enters the interior of the hand grip 14 through an aperture defined by an insulating collar 21 (Fig. 5) and passes down inside of the hand grip and emerges near the inner or pivoted end of the hand grip through an opening defined by another insulating collar 22. A bight 5a of the flexible conductor permits freedom of movement of the handle, the conductor entering the base 2 of the casing through a third insulating collar 23.

A rigid web member 24 formed from the material of the hand grip extends across the outer end of the latter (Fig. 5) and as here illustrated is shaped to provide

an integral, inwardly directed annular flange 25 which is internally screw threaded.

In accordance with the present invention there is provided an extension handle comprising a rod 26 (Fig. 5) which may, for example, be of wood or if preferred, of tubular metal, here shown as of wood and having a metallic ferrule 27 at one end, the ferrule having a screw threaded axial stud 28 designed to engage the screw threads within the annular flange 25 so as rigidly but removably to unite the rod 26 to the hand grip 14. The rod 26 may be of any desired length and may be long enough so that a single length of rod is sufficient for use in propelling the machine along the floor while the operator is in standing position. However, for convenience in shipping and storage it is preferred to employ a sectional extension handle comprising the rod 26 and one or more additional lengths of rod, for example 26^a (Fig. 6). As shown in Fig. 6 the rod 26 is provided at its outer end with a ferrule 28 designed to receive the end of the second section 26^a. If desired these parts may have screw threaded engagement, although ordinarily it will suffice merely to slip the end of the rod section 26^a into the plain ferrule 28. While the extension handle is here shown as comprising two sections 26 and 26^a it is contemplated that a greater number of sections may be employed if desired.

In using the device and assuming that it is to be used for working on elevated objects such as furniture or the like, the hand grip 14 will usually be arranged in the position shown in Fig. 2. The parts may thus be arranged by loosening the wing nut 18 and swinging the grip member 14 down until the shoulder 19 engages the surface 12. The wing nut is then tightened to retain the parts in this position. The disk 9 is then connected to the spindle or shaft 6 and the appropriate working element, for example a sand paper disk or a polishing pad, is secured to the disk 9. The operator then grasps the handle 14 and having started the motor, moves the apparatus about the work as desired, supporting as much of the weight of the machine as is desirable by his grip on the handle 14. If the horizontal position of the handle 14, as shown in Fig. 2, is not convenient for the particular work at hand, the grip member 14 may be swung upwardly, more or less, by loosening the wing nut 18 and after adjusting it to the desired position, again tightening the wing nut.

If it be desired to use the apparatus for sanding or polishing a floor, the extension handle is attached to the end of the hand grip 14, as shown in full lines in Fig. 6, the screw threaded boss 28 at the end of the rod 26 being screwed into the flange 25 at the end of the hand grip, and the additional extension section being then assembled with the rod 26. The operator will then loosen the wing nut 18 and swing the extension handle means to the most convenient position for use in propelling the apparatus along the floor. Usually the best position is that in which the shoulder 20 engages the vertical surface 13 of the boss 11 for in this position it is possible to apply a substantial downward thrust to produce the desired pressure of the working element upon the floor. However, the operator may set the handle means at various positions, as indicated in broken lines in Fig. 6, and if desired may fix the handle in the selected position by tightening the wing nut 18.

While it is most convenient to provide the extension handle by connecting the sectional rod to the end of the hand grip 14 it is contemplated as within the scope of the invention to provide the base 2 of the case with a

socket independent of the hand grip member 14 into which the screw threaded boss 28, at the end of the rod 26, may be inserted, as well as such equivalent means of connecting the extension handle as may be found most convenient and desirable. It is further to be understood that while a desirable construction has herein been suggested by way of example, the invention is broadly inclusive of any and all equivalent arrangements whereby the apparatus is made convenient for alternative use in working on the floor or in working on articles or objects elevated from the floor.

I claim:

1. In combination with a portable scouring and polishing machine of the kind wherein a casing houses an electric motor which drives a short shaft to whose lower end a disk may be attached, the center of gravity of the motor and casing being close to the plane of rotation of the disk so that the latter supports the motor and casing in stable equilibrium, a hand grip shaped to be grasped in one hand for use in manipulating the machine from a kneeling position, said grip being a rigid hollow structure tapering from one end to the other, the smaller end being pivotally attached to the side of the casing near the lower portion thereof, for angular movement in a vertical plane extending radially of the casing, means for adjustably locking the hand grip at any selected angular position within its range of pivotal movement, said grip having at its outer end a rigid transversely extending web in which there is a threaded opening coaxial with the axis of the grip and an elongate staff forming in combination with the hand grip an extension for use when manipulating the machine from a standing position, said staff having a threaded shank at one end engageable with the threaded opening in the web, rigidly to connect the staff to the grip.

2. A portable scouring and polishing machine according to claim 1, wherein the casing has an integral boss having a transverse horizontal hole through it and is provided with abutment surfaces, the grip has a pair of spaced parallel ears which receives said boss between them, said ears having holes therethrough, a bolt pivotally connects the ears to the boss and the grip has at its smaller end shoulders alternatively engageable with each of said abutment surfaces on the boss to limit the arcuate movement of the hand grip.

3. A portable scouring and polishing machine according to claim 1, wherein the hand grip has spaced openings located near the small and large ends thereof for entrance and exit respectively of a flexible conductor cord.
